UNITED STATES PATENT OFFICE

2,436,285

MOTOR OR PUMP

Frank A. Booth, El Segundo, Calif.

Application March 15, 1946, Serial No. 654,737

2 Claims. (Cl. 103—141)

1

The invention aims to provide a new and improved rotary machine which may be constructed for use either as a fluid pump or as a motor, and one which will facilitate the effective use of a fluid in transmitting power. For example, for the transmission of power from a motor to a machine to be driven, one unit, acting as a pump, may be driven by said motor, and another unit, acting as a motor and connected with the machine to be driven, may be actuated by the fluid pumped by the pump unit, and the fluid exhausted from said motor unit may be continuously returned to said pump unit for repumping back to said motor unit. The fluid may be any that is suitable, preferably air laden with oil for lubrication and water for cooling.

Figure 1 of the accompanying drawings is a vertical sectional view substantially on line 1—1 of Fig. 2, the rotor and the vanes being shown in elevation and all of the vane bearings except two being shown in elevation.

Figure 2 is a transverse section on line 2—2 of Fig. 1, the vanes being in elevation.

Figure 3 is a sectional view as indicated by line 3—3 of Fig. 1, the rotor and vanes, however, being in elevation.

Figure 4 is a view similar to Fig. 3 but showing the vanes moved to different positions in the zigzag channel in which they travel.

Figure 5 is a detail sectional view on an enlarged scale, showing one of the seals which are used on the diverging edges of the vanes.

For purposes of explanation, the casing of the machine will be hereinafter referred to as the stator, and the vane-carrying member as the rotor, but the machine could well be so constructed that the reverse would be true. Therefore, the terms "rotor" and "stator" are to be considered as relative rather than limiting. Moreover, while the construction disclosed in the drawings will be specifically described, attention is invited to the possibility of making various changes within the scope of the invention as claimed.

A rotor disk 6 is shown having a hub 7 suitably keyed to a shaft 8 mounted in appropriate bearings 9. When the machine is constructed for use as a pump, this shaft 8 will be suitably power driven but in a turbine structure, said shaft will be driven by the rotor for use in performing any desired work. For purposes of description, it will be considered that the structure disclosed constitutes a turbine.

The rotor disk 6 is formed with radial slots 10 which open through its peripheral edge 11.

2

each slot 10 being provided with flat parallel side walls at right angles to the plane in which said rotor disk 6 is rotatable. Pistons or vanes 12 extend through the slots 10 for movement transversely of the plane of rotation of the rotor disk 6 and each vane is so mounted that it may move from a position in which it projects laterally from one side of the rotor disk, to a position in which it projects laterally from the other side of said disk. Here compare the upper and lower portions of Fig. 2, and see also Figs. 3 and 4. The inner end of each vane 12 is provided with trunnions 13 which may well be formed by the ends of pins extending through said vanes. These trunnions 13 are rockably mounted in openings of rectangular bearing blocks 14 and these blocks are seated tightly in rectangular notches 15 formed in the front and rear walls of the slots 10, said notches opening through the flat sides 20 of the rotor disk 6. The bearing blocks 14 completely fill the notches 15 and have flat outer sides flush with the flat sides of the rotor disk 6. This mounting means for the vanes 12 insures that said vanes may be easily connected with the disk 6 during assembly of the machine and that they may be easily removed when making repairs, and provides for swinging of said vanes to and from the above-mentioned laterally projecting positions.

30 Each vane 12 is formed with an arcuate edge 16 concentric with the axis of its trunnions 13, and with two additional edges 17 which diverge from the vane pivot to the ends of said arcuate edge 16. The vanes extend entirely to the peripheral edge 11 of the rotor disk 6, and said edge 11 is transversely curved in conformity with the curvature of the arcuate edges 16 of said vanes, said edges 11 and 16 being equidistant from the axis of the rotor disk 6.

40 A casing or stator 18 is provided and may well have suitable feet 19 to be secured to an appropriate base or the like. This stator is formed with a circumferentially extending channel 20 (see more particularly Figs. 3 and 4) in which

45 the vanes 12 travel as the rotor disk 6 rotates, said channel 20 being of zigzag form to alternately swing each vane from a position in which it projects laterally from one side of said rotor disk to a position in which it projects laterally from the other side of said rotor disk. This rotor disk 6 and the channel 20 are cooperable in forming two circumferential series of chambers at opposite sides of said rotor disk. In Figs. 3 and 4, the chambers at one side of the rotor disk 11 are shown at 21, and those at the

other side are shown at 21a. The chambers 21 and 21a are disposed in staggered relation with each other and each of said chambers decreases gradually in width from its intermediate portion to its ends. At one end of each chamber 21, 21a, there is a fluid inlet port 22 and at the opposite end of each chamber a fluid discharge port 23 is provided. The ports 22 communicate with a fluid-receiving chamber 24 within the central portion of the stator 18, and a suitable fluid inlet 25 is provided for said chamber. The discharge ports 23 communicate with a continuous chamber 26 within the peripheral portion of the stator 18, and a suitable fluid outlet 27 is provided for said chamber 26. The portion of the rotor disk 6 immediately surrounding the hub 7, is suitably apertured at 28 to permit the passage of fluid from one side of the chamber 24 to the other side.

The channel 20 has a peripheral wall 29 which is concentric with the axis of the rotor disk 6 and contacts with the peripheral edge 11 of said rotor disk. The wall 29 also contacts with the arcuate edges 16 of the pistons 12, and said wall 29 is transversely curved in conformity with the curvature of said arcuate edges 16. The channel 20 is also provided with opposed circumferential side walls 30 which contact with the diverging piston edges 17, and portions of these side walls contact with the flat outer sides of the bearing blocks 14 to prevent them from moving laterally in the notches 15. These side walls 30 also contact with opposite sides of the rotor disk 6 between the chambers 21 and between the chambers 21a, as indicated at 31 in Figs. 3 and 4, and said side walls 30 are twisted alternately in opposite directions to remain in contact with the aforesaid diverging vane edges 17 as the vanes 12 swing alternately in opposite directions.

As to operation, fluid entering the chambers 21 and 21a through the inlet ports 22, acts against the vanes 12 and causes rotation of the rotor disk 6, and the fluid which has acted on any vane, is exhausted through the proper port 23 by means of the next following vane. The machine may be readily reversed by admitting fluid under pressure at 27 (Fig. 2) and exhausting the fluid at 25 (same view).

Suitable fluid-tight seals are provided wherever necessary. Two sealing rings are shown at 32 in Fig. 2, carried by the stator 18 and contacting with opposite sides of the rotor disk 6 between the slots 10 and the openings 28. Arcuate seals 33 are shown for the arcuate edges 16 of the vanes 12, and other seals 34 are provided for the diverging edges 17 of vanes. All of the seals may be spring-pressed outwardly, and a spring for this purpose is indicated at 35 in Fig. 5. In order that the seals 34 and the vane edges 17 can properly follow the zigzag side walls 30 of the continuous chamber 20, said seals and edges are suitably beveled as shown at 36 and 37. Suitable seals 38 are shown for the peripheral edge 11 of the rotor disk 6 and a packing box is shown at 39 for the shaft 8, said packing box being carried by one side of the stator 18. The other side of this stator may well be provided with a removable plate 40 for giving access to a nut 41 securing the rotor hub 7 on the shaft 8.

From the foregoing taken in connection with the accompanying drawings, it will be seen that novel and advantageous provision has been made for carrying out the objects of the invention, and while preferences have been disclosed, attention

is again invited to the possibility of making variations within the scope of the invention as claimed.

I claim:

1. A machine of the class described comprising a rotor having radial slots therethrough, a plurality of vanes extending through said slots for movement transversely of the plane of rotation of said rotor, a stator having a circumferentially extending channel in which said vanes travel as said rotor rotates, said channel being of zigzag form to alternately shift each vane from a position in which it projects laterally from one side of said rotor to a position in which it projects laterally from the other side of said rotor, said rotor and channel being cooperable in forming two circumferential series of chambers at opposite sides of said rotor, the chambers at one side of said rotor being in staggered relation with those at the other side thereof, each of said chambers being gradually decreased in width from its intermediate portion to its ends, said stator having two fluid-conducting chambers surrounded by the aforesaid circumferentially extending channel and disposed at opposite sides of said rotor, said stator having a fluid conductor from its exterior to one of said two fluid-conducting chambers, said rotor having fluid-conducting ports placing said two fluid-conducting chambers in communication with each other, said stator having radial fluid-conducting ports placing said fluid-conducting chambers in communication with one end of the chambers of said two circumferential series, said stator having fluid-conducting ports communicating with the other end of said chambers of said two circumferential series, and also having a manifold communicating with the last mentioned ports.

2. In a machine of the class described, a flat-sided rotor disk having a radial slot opening through its peripheral edge and through its flat sides, the front and rear walls of said slot having opposed rectangular notches at the inner end of said slot and opening through the flat sides of said rotor disk, a vane extending through said slot and having trunnions projecting from its inner end, rectangular bearing blocks having openings receiving said trunnions, said bearing blocks being tightly seated in and filling the aforesaid notches and having flat outer sides flush with the flat sides of said rotor disk, and a stator in which said rotor disk is mounted, said stator having means cooperable with said vane for performing work and for swinging said vane upon said trunnions during rotation of said rotor disk, said stator having side walls contacting slidably with said flat outer sides of said bearing blocks to hold the latter against lateral movement in said notches.
